DRUM-TYPE FEED CONTROL

Julius Wegner, Flushing, N. Y.

Application January 11, 1949, Serial No. 70,160

5 Claims. (CL. 125—16)

1

This invention relates broadly to stone sawing or cutting machines and more particularly to feeding mechanisms for intermittently lowering or feeding the saw blades into the stone to be cut.

The structure of these sawing machines, called gang saws in the trade, usually consists of a frame, which carries a sash in which any number of saw blades from a few to a few hundred may be mounted. The sash frame may be operated in a number of different ways, such as, for instance, by means of a crank shaft and a connecting rod.

For the purpose of cutting through a stone slab, the sash frame, carrying the saw blades, is successively lowered. Heretofore, the lowering of the sash frame or the feeding of the saw blades into the stone has been accomplished either by a separate drive, which operated the feeding screws of the sash frame, or the feeding mechanism has been interconnected with the main drive of the machine, such as the crank shaft, thus operating the feeding screws intermittently by means of gear trains, ratchets, or similar arrangements. The drawback of the latter arrangement has been that the adjustment of the rate of feed has been very cumbersome and necessitated either shutting down these gang saws altogether, which, besides an inevitable loss of time, was likely to result in an uneven cut through the stone slab, or the operator had to climb up to the top of the gang saw in order to readjust the feed, which is an inconvenient as well as a dangerous task. Actuating the sash feed by means of gearing, ratchets, and the like, of course, limits the rate of feed to certain multiples of a given feed. Consequently, the operator would never adjust the most efficient feeding rate, and to prevent jamming the saw blades and doing other damage with too rapid a feeding rate, the operator has a natural tendency to set the feed of the sash frame at a slow enough rate to obviate these calamities under any and all circumstances.

The need has been felt in the trade for many years for a sash frame feed which could (1) be adjusted by the operator with convenience and without danger while the saw is in operation, and which (2) would allow a stepless adjustment of the feed to obtain maximum output regardless of the relative hardness of the stone to be cut.

In my co-pending application Serial No. 50 756,124, filed June 21, 1947, now Patent No. 2,478,957, issued August 16, 1949, there is illustrated a feed control for gang saws which overcomes these shortcomings. It comprises a novel feed control box mounted on the crank shaft 55

2

and includes a pair of slideable bevel gears adapted to be selectively meshed by hand with another bevel gear for changing the eccentric throw of a slide associated with the feed control mechanism.

5 A connecting rod is provided for transmitting the eccentric motion of said slide to a system of crank arms, which act by means of connecting bars on a pair of ratchet devices.

10 The present invention represents a further improvement in such feed controls for gang saws. While the aforementioned feed control has been found efficient and practical, its application to the multitude of different designs of old gang saws necessitates the use of a considerable number of parts which must be made and fitted especially for each such machine.

15 The present invention overcomes this and other objections in that the feed control unit is contained within a rotatable drum or pulley, which may be located near the ratchet devices and may be driven by a chain or belt from any rotating member of the gang saw. Therefore, differences in center distance, for instance, between the driving member and the driven feed control drum, as found in gang saws of different designs, present no difficulties, because in the present invention it is only necessary to vary the lengths of standard chains or belts. The new gang saw feed is, therefore, adapted to be made in standardized units and is preferably mounted on the gang saw structure in close proximity to the sash frame feeding mechanism, usually placed near the top of the gang saw.

20 It is another feature of the present invention to provide a feed control device of the character described including adjusting means which may be inexpensively adapted to be actuated from the operator's natural working position, regardless of the height at which the feed control device is mounted.

25 Another object is to provide a feed control mechanism which is foolproof because the operator need not be near any moving or rotating member when adjusting the rate of feed, and wherein operating gears are employed which are in constant mesh, in combination with braking means for actuating said operating gears selectively to increase or decrease the rate of feed.

30 The foregoing and other features of novel construction in the improved gang saw feeding mechanism will become apparent from the following description, taken in conjunction with the drawings, wherein

35 Fig. 1 is a front elevation of a standard gang

saw in which the novel sash feeding mechanism is incorporated;

Fig. 2 is a plan view, showing the sash feeding mechanism depicted in Fig. 1 and part of the gang saw proper;

Fig. 3 illustrates the spring-lifted brakes in greater detail, which serve for selectively adjusting the feed control mechanism;

Fig. 4 shows a view along line 4—4 of Fig. 3;

Fig. 5 is an enlarged sectional view of the novel feed control device mounted in the drumlike housing;

Fig. 6 shows a right-hand front view of the feed control device in the direction of arrows 6—6 in Fig. 5 with the cover partly broken away.

Gang saw proper

Referring to the general assembly shown in Figs. 1 and 2 of the drawings, the gang saw proper is illustrated more or less diagrammatically because it will be understood that the improved sash feeding mechanism may be used and adapted to any type of gang saw. The main frame of the gang saw is formed by vertical beams or columns 11, interconnected by cross beams 12. A sash frame or sash 13 of any conventional design is mounted in said main frame or main structure and may be horizontally guided by slides 14. Sash 13 may be reciprocated by any suitable means, such as connecting rod 15, pivotally secured to sash frame 13 and actuated by means of crankshaft 16, as shown. Crankshaft 16 carries flywheels 17 and 18, which latter is usually driven by flat belt or similar means by a prime mover, such as an electric motor (not shown).

As the sash frame 13, which may carry any required number of saws, is reciprocated, it is intermittently and progressively lowered to feed the saws into the stone to be cut. The means shown as an example comprise vertical threaded spindles 19, which are journaled in bearings 20, supported by the uprights 11 and guide plates 21, threaded on said spindles 19, which carry at their upper ends bevel gears 22 in mesh with bevel gears 23 on shafts 24. All spindles 19 are driven in synchronism by means of said bevel gears 22, 23, and additional bevel gears 25, when shafts 24 are rotated.

The gang saw, as briefly described above, is identical to the one shown in my co-pending application Serial No. 756,124, filed June 21, 1947, now Patent No. 2,478,957, issued August 16, 1949, and is of altogether conventional design. It does not form part of the present invention.

Sash frame feed

Feed control drum 26 houses an instantaneously adjustable crank and is carried by stationary outside sleeve 27, which may be fastened by bolts or the like to the structural frame of the gang saw or some auxiliary structure 28, formed by timbers or the like (Figs. 1 and 2). The feed control drum 26 is driven by any suitable means, such as a chain or a belt 29 and pulley 30, fast to crankshaft 16. Connecting rods 31 and 32 are provided to transmit the eccentric motion created by crank or slide 33 of the feed control drum 26 to ratchet devices or one-way clutches 34 and 35, respectively, in the manner shown. These one-way clutches are mounted on clutch shaft 36, which is journaled in bearings 37 and 38, respectively, supported by the machine proper or by the auxiliary structure 28. Clutch shaft 36 also carries pinion 39 in mesh with gear 40 on main feed shaft 41. The latter is journaled in bearings 42 and 43.

Gear 40, whose hub 44 may form one-half of a jaw clutch, is freely rotatable on shaft 41, to which complementary clutch half 45 is slidably keyed, so that member 45 may be brought into and out of engagement with clutch half 44 by means of a hand lever or other suitable arrangements (not shown). Shaft 41 also carries fast and loose pulleys 46 and 47. These pulleys are arranged for rapid adjustment of the sash frame 13 in a vertical direction. A separate drive is generally used for this purpose, such as an electric motor with belt driving said pulleys 46 and 47. When employing this rapid feed, jaw clutch 44—45 is in disengaged position (as shown in Fig. 2), thereby rendering the work feed from feed control drum 26 inoperative. The rotation of shaft 41, whether caused by feed control drum 26 or by said rapid height adjustment, is transmitted to the several shafts 24 of the machine proper by means of gear 48, fast to shaft 41, and pinion 49, fast to one of the feed shafts 24, as shown. As previously described, the sash frame 13 is thereby evenly lifted or lowered by means of vertical spindles 19. When the rapid height adjustment is not to be used, the belt is shifted to the loose pulley, thereby rendering this auxiliary rapid feed means inoperative.

It is pointed out that the previously mentioned one-way clutches 34 and 35 are of conventional design and can only impart clockwise rotation to shaft 36. Referring especially to Fig. 1, it will be seen that connecting rod 32, actuated by crank 33, is connected to an extension or arm of one-way clutch 35, which arm protrudes substantially above the center line of shaft 36. Hence, assuming crank 33 to be revolving in clockwise direction and to be at top dead center position at the instant depicted in Fig. 1, it will be evident that clutch 35 is also rotated clockwise around shaft 36. As one-way clutch 35 is designed so that it will impart only clockwise rotation to shaft 36, the latter will be rotated in clockwise direction at this instance. In fact, this clockwise actuation of shaft 36 by clutch 35 will prevail substantially during the complete upper half of the crank throw of slide 33, namely, starting at a point about 90 degrees before the crank position shown in Fig. 1 and ending at a point about 90 degrees after said top dead center position of crank 33 shown in Fig. 1. It will also be noted in Fig. 1, that the other connecting rod 31, also actuated from common crank 33, is connected to an extension or arm of one-way clutch 34 which protrudes substantially below the center line of shaft 36. Hence, at the top dead center position and clockwise rotation as viewed in Fig. 1 and about described, said crank 33 will rotate one-way clutch 34 in counter-clockwise direction. Clutch 34, however, is of identical design as clutch 35 and can only impart clockwise rotation to shaft 36. Consequently, the clockwise rotation of crank 33 will at this particular instant rotate clutch 34 in counter-clockwise direction and, therefore, clutch 34 will be free-wheeling during the whole upper half of the crank throw previously defined. During the lower half of the crank throw of slide 33, conditions will obviously be reversed. Clutch 34 will be rotated in clockwise direction and hence impart a second feeding impulse to shaft 36; clutch 35 will be rotated in counter-clockwise direction and, hence, will be free-wheeling. Thus, when the adjustable slide or crank 33 of feed control drum 26 rotates, the one-way clutches 34 and 35 will alternately rotate shaft 36 in clockwise direction. It will be understood that, by using

two ratchet devices, 34 and 35, the screws 19 of the gang saw are actuated twice for each revolution of said control drum 26. This double feed has proven very advantageous in cutting certain grades of stones and has increased the cutting rate very appreciably.

If it is desired to impart to the sash frame 13 only one feeding movement for each revolution of said drum 26, either of the bars 31 or 32 may be disconnected at the drum end and fastened to some stationary part of the structure. If bar 31 is disconnected from drum 26, for instance, one-way clutch 34 is rendered inoperative as regards imparting rotation to shaft 36 but will act as a brake to prevent any torsional springback of shaft 36 which might otherwise be caused by the elastic deformation in the various links of said feeding mechanism. It should also be observed that the free wheeling clutches will act similarly during the double feed cycle. In other words, this design positively eliminates any undesirable torsional springback for the single as well as the double feed cycle. Feeding inaccuracies, such as found in conventional feed mechanisms, are, therefore, done away with.

Feed control drum

Referring to Figs. 5 and 6, the feed control device 26 is so arranged that it may be conveniently adjusted to produce any desired eccentricity from zero to maximum, while the gang saw is in operation. The feed control mechanism is mounted within a drum or housing 50, from which a suitable hub 51 extends for fastening to a sleeve 52 by means of set screws 53 or the like. Whenever pulley or drum 50 is rotating, sleeve 52 will participate in this rotation. Bushings 54 and 55 are provided in outside sleeve 27 to rotatably support sleeve 52. Outside sleeve 27 is provided with pads 56, through which suitable bolts may extend into the structure of the gang saw proper in order to support the feed control device 26 with its associated mechanisms. An adjusting spindle 57 is rotatably mounted in thrust bearing 58 and journalled in bearings 59 and 60. It has keyed to it at its one end bevel gear 61, in mesh with bevel gear 62, fast to shaft 63, which is concentric to and rotatably carried by a sleeve 64. A brake drum 65 is keyed to the end of shaft 63 and located by threaded nut 66. Another bevel gear 67 is also in mesh with bevel gear 61 on spindle 57 and is keyed to one end of the aforementioned sleeve 64, which carries at its other end a brake drum 68, keyed or otherwise fastened thereto. Bushings 69 and 70 rotatably support sleeve 64. The adjustable slide 33 is in threaded engagement with spindle 57. A stub shaft 71 is threaded into slide 33 and carries the hubs of the previously mentioned connecting bars 31 and 32. A washer 72 and threaded nut 73 are provided to position the aforementioned hubs.

It will be seen that, when spindle 57 is rotated, slide 33 with its stub shaft 71 may be eccentrically adjusted from the zero position shown in Figs. 5 and 6. A suitable opening 74 may be provided in cover 75, fastened to housing 50 by means of screws, as indicated at 76, to allow this radial adjustment of slide 33. The latter comprises four arms 77, 78, 79, and 80. Circular rods 81 and 82 are mounted in bosses 83 and 84, respectively, of housing 50. Said rods 81 and 82 extend through suitable bores at the ends of arms 78, 79 and 77, 80, respectively, for guiding the slide 33 and for providing braking or frictional clamping surfaces for maintaining slide 33 in its adjusted position, 75 speed and in the same direction as pulley 50, be-

if not acted upon by spindle 57. To vary the frictional resistance between rods 81 and 82 and their associated clamping arms 78, 79, and 77, 80, respectively, the ends of said arms are slotted and Allen head set screws 85 are provided to vary the clamping action of these arms on rods 81 and 82. It is important to provide a certain amount of frictional resistance to the movement of slide 33, as otherwise the rotation of pulley 50 might tend to rotate the spindle 57 inadvertently and thus cause undesired adjustments. Of course, screws 85 may not be tightened to such an extent as to lock the slide 33 to rods 81 and 82, as otherwise an adjustment of slide 33 by spindle 57 would be obviously impossible. Cover 75 is provided with suitable slotted openings 86 to facilitate tightening of screws 85 in any position of slide 33 without removing the cover.

The feed control drum 26 is usually mounted at a considerable height. Therefore, an indicator rod 87 is shown to be fastened to one of the hubs of the connecting rods, such as to rod 32, as shown in Fig. 5, by means of fork 88 and pin 89. At its lower end, rod 87 is freely guided in element 90. By graduating the lower end of rod 87, as indicated at 91, the operator has a convenient check at all times on the eccentricity of slide 33.

Referring now to Figs. 3 and 4, it will be seen that the brake bands 92 and 93 are ordinarily lifted off brake drums 65 and 68 by the action of springs 94 and 95, which may be supported by a rod 96, fast to structure 28. Chains 97 and 98 are fastened at one end to brake bands 92 and 93, respectively, and at the other ends to a double crank hand lever 99, suitably pivoted on the main structure of the machine. Figs. 3 and 4 show this hand lever 99 in neutral position, thus exerting no pull on either of the chains 97 or 98. However, by turning lever 99 to the right from the position illustrated in Fig. 3, chain 98 will be tightened, and brake band 93 will be brought in contact with its associated brake drum 68 against the tensioned spring 95, thus tending to retard or stop the motion of this brake drum. When swinging hand lever 99 from its neutral position to the left, chain 97 will be tightened, thus pressing brake band 92 in engagement with brake drum 65 against the action of spring 94. This results in retarding or stopping brake drum 65. It will thus be seen that, when tightening brake band 92 by means of chain 97, the other chain 98 will become loose, and vice versa. This double crank hand lever 99, therefore, serves the twofold purpose of conveniently applying a braking action to either of the brake drums 65 and 68 and, at the same time, preventing the operator from actuating both brakes simultaneously.

Feed adjustment

Figs. 5 and 6 show the feed control mechanism in neutral position, that is, stub shaft 71 is in alignment with the center of rotation of pulley 50. In this position the hubs of connecting bars 31 and 32 are concentric with the center of rotation of pulley 50, and connecting bars 31 and 32 will remain stationary; hence, the feed to the gang saw is zero, despite the fact that pulley 50 is rotating. The brake bands 92 and 93 are assumed to be in their normal, inoperative position, namely, lifted off the brake drums 65 and 68, as clearly indicated in Figs. 3 and 4. Thus shaft 63 with its brake drum 65 and bevel gear 62, and sleeve 64 with bevel gear 67 and associated brake drum 68, will be free to rotate together at the same speed and in the same direction as pulley 50, be-

cause bevel gear 61 is in mesh with bevel gears 67 and 62. It should be noted that bevel gear 61, being fast to spindle 57, partakes of any rotary movement of housing 50 but does ordinarily not rotate around its own axis. However, by retarding or stopping one of the brake drums 65 or 68, the eccentricity of slide 33 may be increased or decreased, as desired. As mentioned before, shaft 63 and sleeve 64 rotate normally at the same speed and in the same direction as pulley 50 due to the meshing bevel gears 61, 62, and 67. Bevel gears 62 and 67 will, therefore, be caused to turn around their own axes at the speed of pulley 50. Bevel gear 61, on the other hand, has normally no rotation around its own axis and is furthermore prevented from unintended rotation by the clamping surfaces 77, 78, 79, and 80 of the slide 33, as previously described. However, as soon as, let us say, bevel gear 62 is prevented from rotating or retarded in its rotation around its own axis by applying a braking action to brake drum 65, bevel gear 61 will respond by a compensating rotation in one direction and thus accomplish the desired eccentric displacement of slide 33. Similarly, when bevel gear 67 is stopped or retarded by a braking action on brake drum 68, bevel gear 61 will be forced to rotate in the respective opposite direction and cause the slide 33 to be displaced accordingly.

The length of the chain or belt driving the drum 26 may obviously be altered with negligible expense. The lengths of the chains, ropes, or other means for applying the brakes may also be changed with ease. The application of standardized feed control units to the most varied equipment is, therefore, rendered practical.

In addition, the mutually exclusive action of the double crank lever safeguards the feed control device by preventing the operator from accidentally applying both brakes simultaneously.

The eccentricity of the adjustable slide may be varied in infinite steps from zero to a maximum, and the feed control device may be adapted to impart one or two feeding impulses to the sash of the gang saw or any other equipment requiring a similar feed which must be adjusted while in operation.

While I have shown and described, by way of example, mechanism for attaining the stated objects, I wish to have it understood that various changes or modifications may be made within the scope of the claims hereto attached without departing from the spirit of the invention.

Having thus described my invention I claim:

1. In an adjustable feed control device, a drum adapted to serve as a housing, driving means contacting the peripheral surface of said drum for rotating said drum in synchronism with the operation of a machine, a slide associated with said drum for producing a crank motion; adjustable means for changing the eccentric throw of said slide while said drum is rotating including normally inoperative braking means and manually operable means for applying said braking means to actuate said throw adjusting means to selectively increase or decrease the eccentric throw of said slide; said slide having adjustable frictional clamping surfaces for subjecting said slide to a predetermined frictional resistance to maintain said slide in position when said throw adjusting means are inoperative, and an indicator rod operably connected with said slide for indicating the magnitude of the eccentric throw of the latter.

2. A feed control device according to claim 1, at the same speed as said housing, selectively op-

in combination with two ratchet mechanisms operatively connected with said slide and adapted to impart two feeding impulses to the feeding mechanism of a machine for each revolution of said drum.

- 5 3. In a mechanism for intermittently actuating the feed of a machine, feed control means comprising a housing adapted to serve as a pulley, driving means for rotating said housing in synchronism with the operation of the machine, a slide radially adjustable in said housing for producing a crank motion and having frictional clamping surfaces including adjustable means for subjecting said slide to a predetermined degree of frictional resistance at all times, adjustable stroke control means for displacing said slide while said feed control means is rotating, two one-way clutch devices operatively connected with said slide and adapted to impart two feeding impulses to the feed of the machine during each revolution of said feed control means, said one-way clutch devices being adapted to alternately lock the feed against torsional spring-back during part of their operating cycle.
- 10 20 25 30 35 40 45 50 4. In mechanisms for progressively feeding the reciprocating sash frame of stone cutting saws towards the work material, a feed control device comprising, a rotatable pulley adapted to serve as a housing, means for rotating said pulley in synchronism with the reciprocating sash frame, a slide associated with said pulley for producing a crank motion, a spindle in threaded engagement with said slide for displacing said slide eccentrically, a pair of drive shafts rotatably mounted substantially at right angles to said spindle, meshing bevel gears carried by said spindle and by said pair of drive shafts, normally inoperative braking means associated with said pair of drive shafts including means for selectively applying a braking action to retard the rotation of either one of said drive shafts, thereby causing a compensating rotation of said spindle in either one of two directions with a consequent increase or decrease in the eccentricity of said slide while said pulley is rotating, adjustable friction surfaces for maintaining said slide in its adjusted position, and two ratchet devices operatively connected with said slide for imparting two consecutive feeding impulses during each revolution of said pulley for feeding the sash frame towards the work material.

- 55 60 65 70 5. In a mechanism for imparting intermittently two feeding impulses during each cycle of a machine, a housing adapted to serve as a pulley, a sleeve secured to said housing, means for rotatably supporting said sleeve, means for rotating said housing with its associated sleeve in synchronism with the operation of the machine, a slide associated with said housing for producing a crank motion, a spindle located within said housing and in threaded engagement with said slide for displacing said slide eccentrically when said spindle is rotated with respect to said slide, adjustable friction surfaces on said slide adapted to permit displacement of said slide when acted upon by said spindle but normally maintaining said slide in a fixed position with respect to said housing, a second sleeve rotatably mounted inside said first sleeve, a shaft rotatably disposed within said second sleeve, driving means secured to said second sleeve and to said shaft, other driving means secured to said spindle and cooperating with said first-mentioned driving means to normally rotate said shaft and said second sleeve

erable braking means associated with said shaft and said second sleeve adapted to retard or stop the motion of said shaft or that of said second sleeve for inducing a compensating rotation of said spindle in either one of two directions while said housing is rotating; two one-way clutch devices operatively connected with said slide and adapted to impart two consecutive feeding impulses to the machine during each revolution of said housing.
